UNITED STATES PATENT OFFICE.

FRANK GABRIEL AND LAWRENCE G. SHOOK, OF LOS ANGELES, CALIFORNIA; SAID SHOOK ASSIGNOR OF ONE-HALF OF HIS RIGHT TO GERALD A. MACLEAN, OF PASADENA, CALIFORNIA.

INTERRUPTER-POINT GRINDER.

Application filed May 29, 1924. Serial No. 716,702.

This invention is an interrupter point grinder and consists of the novel features herein shown, described and claimed.

An object is to make a simple device which will hold any of the various constructions carrying interrupter points and grind flat faces upon the interrupter points.

Other objects and advantages will appear from the drawings and specification.

10 The drawings illustrate the details of construction and operation of an interrupter point grinder embodying the principles of our invention.

15 Fig. 1 is a perspective interrupter point grinder set up for holding and grinding one form of interrupter point.

Fig. 2 is a side elevation as indicated by the arrow 2 in Fig. 1, parts being broken away and shown in section.

20 Fig. 3 is a plan view of the parts shown in Figs. 1 and 2 and showing a different operation.

Fig. 4 is a plan view analogous to Fig. 3 showing still another operation.

25 Fig. 5 is a side elevation as indicated by the arrow 5 in Fig. 4.

The details of construction and operation shown in the drawings are as follows:

30 The base 1 is rectangular in plan and has a finished horizontal upper face 2 and a second finished horizontal upper face 3, there being a vertical finished face 4 connecting the adjacent edges of the faces 2 and 3. The face 2 is substantially twice as wide as the face 3.

35 The sliding carrier base 5 is rectangular in plan and has a finished lower face 6 so that the base 5 will slide freely upon the face 2, and has a finished side face 7 to slide freely against the face 4. Round pins 8 and 9 are fixed in the carrier base 5 in transverse alinement and in a line crosswise of the faces 2, 3 and 4. Expansion coil springs 10 and 11 are mounted upon the carrier base 5 around the pins 8 and 9. The clamp carrier 12 has vertical openings to receive the pins 8 and 9 loosely and rests upon the springs 10 and 11, the tensions of the springs being exerted to hold the carrier 12 elevated.

40 A slot 13 is formed from the end of the clamp carrier 12 which extends over the face 3 and a clamp screw 14 is inserted horizontally through the material at one side of the slot 13 and tapped through the material at the other side of the slot so that

by tightening the screw the clamping tongues 15 and 16 on opposite sides of the slot 13 are drawn toward each other. Vertical circular openings 17 are formed along the slot 13, the openings being of various sizes as required to receive and clamp posts, studs, binding screws and interrupter point carriers 18. A piece 19 of a sheet of emery cloth, emery paper, sand paper or other suitable abrasive material is laid upon the face 3 and the article 18 to be ground is inserted into the desired one of the openings 17 and clamped by manipulating the screw 14, and then the carrier 12 is manually pressed downwardly to bring the face 7 of the interrupter point into contact with the abrasive material 19 and the base 5 and carrier 12 are manually moved longitudinally to produce the grinding action. In Fig. 1, the grinding action will be a straight reciprocating motion if the face 7 bears against the face 4 and the point of contact upon the abrasive material 19 may be varied in parallel lines by moving the base 5 to or from the face 4. In Fig. 3, the carrier 12 is applied only to one of the pins 8 or 9, and then the carrier 12 may be operated with a compound rotary reciprocating and longitudinal reciprocating motion.

45 A series of holes 20 is bored horizontally through the carrier 12 in the vicinity of the vertical openings receiving the pins 8 and 9. A clamp consisting of an irregular head 21, a screw 22 extending from the head and a wing nut 23 upon the screw is used for clamping and holding constructions carrying interrupter points, the constructions being such that they cannot be clamped in the manner shown in Figs. 1, 2 and 3. In Figs. 4 and 5 the interrupter construction shown 50 comprises a resilient flat straight member 24 carrying an interrupter point 25 at one end and having a Z-shaped arm 26 at the other end. When it is desired to grind the point 25, the carrier 12 is raised from the pins 8 and 9 and turned end from end and the members 24 and 26 are placed edgewise against the side of the carrier 12 with the screw 22 extending through one of the holes 20 and the nut 23 applied to hold the interrupter rigid while the point 25 is ground by reciprocation upon the abrasive material 19.

55 Thus we have produced an interrupter point grinder comprising a base having two 100

horizontal finished upper faces on different levels and a finished vertical face connecting confronting edges of the horizontal faces, a sliding carrier base adapted to operate upon the lower finished face, pins projecting upwardly from the sliding carrier base, expansion springs upon the pins, a clamp carrier slidably mounted upon the pins against the springs, and means for clamping articles having interrupter points to the clamp carrier so that the interrupter points may be engaged with abrasive material upon the upper finished face and moved to grind the points.

15 Various changes may be made without departing from the spirit of our invention as claimed.

We claim:

An interrupter point grinder comprising

a base having two horizontal finished upper faces on different levels and a finished vertical face connecting confronting edges of the horizontal faces, a sliding carrier base adapted to operate upon the lower finished face, pins projecting upwardly from the sliding carrier base, expansion springs upon the pins, a clamp carrier slidably mounted upon the pins against the springs, and means for clamping articles having interrupter points to the clamp carrier so that the interrupter points may be engaged with abrasive material upon the upper finished face and moved to grind the points.

20 In testimony whereof we have signed our names to this specification.

FRANK GABRIEL
LAWRENCE G. SHOOK.
